UNITED STATES PATENT OFFICE

JAMES L. CAMPBELL, OF MONTICELLO, GEORGIA.

BACK-BAND.

SPECIFICATION forming part of Letters Patent No. 508,128, dated November 7, 1893.

Application filed April 22, 1893. Serial No. 471,445. (No model.)

To all whom it may concern:

Be it known that I, JAMES L. CAMPBELL, a citizen of the United States, residing at Monticello, in the county of Jasper and State of Georgia, have invented certain new and useful Improvements in Back-Bands; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 The special object of my invention is to make a back band for horses which shall be strong, durable, easy to the animal and convenient in use.

Figure 1 of the drawings is a plan view of 20 the back band. Fig. 2 a cross-section on dotted lines xx and Fig. 3 a longitudinal section of one end on the dotted line yy of Fig. 1.

In the drawings, A represents the back band which is formed of seven layers or thicknesses, the layers B, five in number being what is known as "sail ducking" while the two layers C C are made of "burlap" packing of wool, hair or other suitable material. The layers B are all in one piece and folded 25 of the desired widths with the burlap or equivalent soft packing between the folds. It is then stitched longitudinally with five 30 seams, four beside the edge seam and preferably at equal distances apart.

D D are two leather strips, one at each end 35 of the band and on the outer face thereof the said strips being sewed to the band all around the edges so as to form a rectangular endless seam E. To these leather strips D D, I rivet one end of a perforated leather 40 strap F which passes through the loop g of a spring snap hook G and are each arranged in the middle of the strip. This equalizes the strain on the whole width of the band. The leather is folded around the ends of the band 45 and the end held by the seam E, thus protecting the band ends from abrasion.

The buckle H attached to the strip, under the strap, enables the band to be adjusted to horses of different girth so that the same 50 belly-band may be used on larger or smaller horses.

What I claim as new, and desire to protect by Letters Patent, is—

As an improved article of manufacture, a 55 backband made of a single piece of folded duck padded between the folds, stitched longitudinally, and having the ends bound with leather, an adjustable loop and snap hook being secured to the leather and the latter riveted to the duck as shown and described.

In testimony whereof I affix my signature in presence of two witnesses.

JAMES L. CAMPBELL.
